UNITED STATES PATENT OFFICE.

WILDER R. SHECKLER, OF GREENVILLE, PENNSYLVANIA.

EXPANSION-UNION.

No. 907,187.

Specification of Letters Patent.

Patented Dec. 22, 1908.

Application filed January 29, 1908. Serial No. 413,216.

To all whom it may concern:

Be it known that I, WILDER R. SHECKLER, a citizen of the United States, residing at Greenville, in the county of Mercer and State of Pennsylvania, have invented certain new and useful Improvements in Expansion-Unions; and I do hereby declare the following to be a full, clear, and exact description of the invention, such as will enable others skilled in the art to which it appertains to make and use the same.

The main object of my invention is to enable train-pipe couplings to be automatically disconnected by separation of the cars without liability of injury to the equipment.

An air line on freight and passenger trains usually carries about seventy pounds pressure to the square inch. It is a demonstrated fact that to uncouple the air-hose on a line with this pressure requires a straight-away pull of over three-hundred pounds, which would damage the rubber hose-sections or break the pipe-connections under the cars. This necessitates a man going in between the cars to uncouple the hose. All railway companies insist upon such manual uncoupling before separation of the cars. It is however a dangerous operation for a man to make.

The purpose of my invention is to allow the hose to be uncoupled without damage to the hose-sections or pipe-connections, and without requiring a man to go in between the cars for uncoupling. This is accomplished by providing in the pipe-line an expansion union which normally maintains an air-tight joint, but which is adapted, by pull on the hose when the cars are separated, to break or open the joint slightly and allow escape of air, thus relieving the train-line pressure and allowing the coupling-heads to fall apart.

The invention will hereinafter be first fully described by reference to the accompanying drawings, which form a part of this specification, and then more particularly pointed out in the appended claims.

In said drawings: Figure 1 is a side view of an ordinary train-pipe connection, consisting of flexible hose-sections coupled together, as in use for air and steam lines, and showing an application of my invention thereto. Fig. 2 is an enlarged side elevation, with parts broken away and parts in section, of the expansion-union together with the coupling-head and adjacent hose-section which are joined by said union. Fig. 3 is a cross-section on line 3—3 of Fig. 2, looking

in the direction of the arrow. Fig. 4 is a central longitudinal section of the expansion-union on a still larger scale. Fig. 5 is a perspective view of the male member of the expansion-union, the same consisting of a metallic thimble which is adapted to fit on the nipple of the coupling-head. Fig. 6 is a detail view of the union-gasket. Fig. 7 is a perspective view of a fragmentary portion of the metallic sleeve or nipple which carries the coupling-nut of the union.

In Fig. 1, the train-pipes *a* of adjacent cars are shown provided with the regular angle-cocks *b*, from which are swung the flexible hose-sections *c*, usually of rubber, the latter being coupled together by coöperative coupling-heads *d*. Between the coupling-heads and hose-sections are interposed expansion-unions *e*. Said coupling-heads *d* are or may be of the type commonly employed for coupling the hose of air and steam train-pipe lines, as well understood by those familiar with the art.

Fig. 2 shows a fragment or end portion of one of the hose-sections *c*, carrying its coupling-head *d* for coupling with the similar coupling-head carried by the other hose-section. In the ordinary train-pipe equipment, the free or swinging end of the hose-section is usually fitted on and bound or clamped around the nipple 1 of the coupling-head *d*, said nipple being usually longer than as shown in this figure. In the present case, however, the nipple is stubbed or shortened and is joined to the hose by the interposed expansion union, as before mentioned. For this purpose, the hose-section *c* is attached to and carries a metallic nipple or short pipe-section 2, which preferably has a threaded or corrugated portion 3 fitted and secured in the end of the hose, the latter being bound or clamped thereon, as indicated at 4. As shown in the several figures, this nipple 2 has an exposed portion extending beyond the end of the hose and provided at its end with an external flange 5. The bore of the nipple 2 is preferably substantially the same as that of the nipple 1 of the coupling-head *d*. Mounted on and loosely inclosing the exposed portion of the nipple 2 is a coupling-nut 6, having a tubular extension or sleeve 7 made at its rear end with an internal flange 8. The bore of the coupling-sleeve 7, including the internally-threaded portion of the nut 6 proper, is adapted to slip loosely and freely over the flange 5 on the end of the nipple 2;

while the flange 8 of the nut-sleeve 7 will likewise slip loosely and freely over the body of the nipple; provision thus being afforded for escape or leakage of air through the coupling-nut. A spiral spring 9 encircles the nipple and is compressed between the flange 5 on the latter and the flange 8 on the nut-sleeve. In assembling the parts, the spring 9 is of course first slipped on the nipple 2, and 10 the coupling-nut is then slipped on from its smaller end before the nipple is attached to the hose.

A metallic thimble 10, having an internally-threaded portion, is screwed on the 15 stubbed nipple 1 of the coupling-head *d*, the end of the latter being screw-threaded for that purpose. The portion of said thimble 10 which extends beyond the end of the nipple 1 is preferably thickened at 11 to reduce 20 its internal diameter to that of the nipple 1, and a rubber or elastic ring 12 is interposed and compressed between the end-wall of such thickened portion 11 and the end of the nipple 1. Said thimble 10 is made exteriorly with a male screw 13, shown formed on a raised surface. This male screw 13 is adapted 25 for engagement by the female screw 14 of the coupling-nut 6, whereby the flange 5 of the nipple 2 is adapted to be brought against 30 the thimble 10, by screwing the coupling-nut on the latter against the resistance of its housed spring 9, as shown in the drawings and as will be fully understood. The male screw 13 on the thimble is shown notched at 35 intervals, indicated at 15, to allow engagement by a wrench for screwing the thimble on the nipple, and also serving a further purpose presently to be considered.

An air-tight joint is made between the 40 thimble 10 and the nipple 2. For this purpose, one of said parts, preferably the thimble 10, is made with a projecting annular boss 16 adapted to enter in a recess or enlarged bore 17 in the other part, preferably 45 in the flange 5 of the nipple 2. The arrangement shown is preferred, though obviously it may be reversed. A rubber ring or elastic gasket 18 is stretched over or fitted around the boss 16 and is adapted to seat snugly 50 against the flange 5, the face of the latter being desirably beveled or concave as shown, and the confronting face of the gasket 18 being formed to fit therein. If desired, another gasket may be placed in the recess 17 55 to be engaged and compressed by the boss 16.

The parts of the expansion union being coupled as shown in Figs. 2 and 4 of the drawings, the operation is as follows: Under normal conditions, the spring 9, which may 60 be regulated to the desired pressure by adjusting the coupling nut 6 on the thimble 10, will maintain an air-tight joint between the thimble 10 and nipple 2. But when the railway-cars are uncoupled and separated, as 65 the cars commence to move apart the coup-

ling hose (only one section of which is represented in Fig. 2) are drawn taut; and, as soon as a pull of a few pounds, depending on the tension of and sufficient to compress the spring 9, is made, the joint at 16, 18, 5 70 is broken or separated sufficiently to allow air to escape through the nut-cylinder and pass out through the notches 15 in the male screw 13 and through the opening in the flange 8, 75 thus relieving the train-line pressure and allowing the connected coupling-heads to fall apart under pull of the opposite hose-sections.

It is obvious that the male screw 13 might 80 be formed directly on the nipple 1 and the coupling-nut 6 arranged to screw on said nipple, so that for the purposes of my invention the thimble 10 may be considered as virtually a part of the nipple of the coupling 85 head. It is also obvious that the coupling-nut with its inclosed spring might be swiveled on the said nipple 1, or on the thimble 10, and arranged to screw on a male thread 90 suitably provided on the nipple 2, this being only a reversal of parts.

The expansion-union described is most suitably located adjacent to the coupling-head, that is between the nipple of the coupling-head and the hose-section; but it might as well be 95 arranged at the other end of the hose section, that is between the fixed end of the hose-section and the nipple of the angle-cock which is customarily located at the end of the iron train-pipe; or it might be placed at an intermediate point in the hose, though the arrangement shown is preferred as the most practicable and efficient. It might also be placed at any other point in the train-pipe 100 where the latter is subjected to tension by 105 separation of the cars and pulling apart of the coupling. The union is of course equally applicable to train-pipe lines for air or steam.

While a coupling-nut engaging a male screw is the preferred mode of fastening the 110 union, yet the parts may be fastened by other well-known means, such as bolted flanges; it being sufficient that the fastenings be arranged to effect compression of the spring which yieldingly holds the abutting 115 ends of the nipples in fluid-tight contact.

Having thus described my invention, what I claim and desire to secure by Letters Patent is:

1. In a flexible train-pipe connection, hose-sections having an intermediate coupling designed to be disconnected by the pulling apart of the hose-sections when the cars are separated, and a normally fluid-tight or non-leakable pipe-joint in the flexible connection 125 adapted to be opened by the pull of the hose to allow escape of fluid, thereby relieving the train-line pressure and allowing disconnection of the coupling without tearing the hose or damaging the train-pipe connection. 130

2. In a train-pipe connection, a flexible hose-section extending from a train-pipe and carrying a coupling-head for connection with the coupling-head of another hose-section, one end of said hose-section having a metallic nipple adapted to make a fluid tight joint with another nipple, as that of the coupling-head, a coupling-member loosely-mounted on one of said nipples adapted for fastening 10 on the other nipple, and a spring arranged for compression between said coupling-member and the nipple on which it is mounted, the force of said spring yieldingly holding said nipples in fluid-tight contact, whereby 15 pull of the hose will open the joint and relieve the fluid-pressure to allow easy disconnection of the coupling-heads.
3. In a train-pipe connection, a flexible hose-section extending from a train-pipe and carrying a coupling-head for connection with the coupling-head of another hose-section, one end of said hose-section having a metallic nipple adapted to make a fluid-tight joint with another nipple, as that of the 20 coupling head, a union between said nipples including a spring holding them in fluid tight contact, whereby pull of the hose will open the joint and relieve the fluid-pressure to allow easy disconnection of the coupling- 25 heads.
4. In a flexible train-pipe connection, an expansion union comprising nipples whose abutting ends are arranged to form a fluid-tight joint, a coupling-nut on one nipple arranged to screw upon the other, and a spring in said coupling-nut arranged to be compressed between a shoulder on the nipple and a shoulder in the nut-sleeve, the force of said 30 spring normally effecting a fluid-tight joint between said nipples, and the coupling-nut having provision to allow escape of fluid-pressure therefrom when said joint is opened against resistance of said spring, the nipples being operably separable, for the purposes 35 described.
5. An expansion union comprising opposed nipples whose abutting ends are arranged to form a fluid-tight joint, the end of one nipple having an external flange, a 40 coupling-nut loosely arranged on the latter nipple and adapted to slip loosely over said flange, the nut case having an internal flange which loosely surrounds the nipple on which said coupling-nut is mounted, a compression-spring arranged in the coupling-nut between the two flanges, and a male screw on the 45 other nipple adapted for engagement by said coupling-nut, whereby when the parts of the union are coupled the spring normally holds 50 the nipples in fluid tight contact while allowing separation and release of fluid pressure which may escape through the loosely fitted

coupling-nut, the nipples being operably separable.

6. An expansion union comprising opposed nipples whose ends are arranged to make a fluid-tight joint, a male screw on one nipple having at least one notch extending across its threads, a coupling-nut swiveled on the other nipple and having an inclosed 65 spring arranged to be compressed between a shoulder on said latter nipple and a shoulder in the nut-casing, said coupling-nut adapted to engage said male screw, whereby the spring will yieldingly hold the nipples in 70 fluid-tight contact while allowing separation and relief of fluid pressure which may escape through the aforesaid notch in the male screw, the nipples being operably separable.

7. An expansion union comprising a thimble and a nipple whose abutting ends are adapted to form a fluid-tight joint, a coupling element loosely arranged on one of said parts and adapted for fastening on the other, and a spring arranged for compression between 80 said coupling element and the part on which it is mounted, the said nipple being adapted for attachment to the end of a hose section, while the said thimble is adapted for screwing on the nipple of a pipe member the nipples being operably separable to allow an escape of pressure.

8. An expansion union comprising a thimble and nipple, one having a recessed flange and the other having a projecting boss designed to enter said recess, whereby a gasket can be fitted around said boss to seat against said flange, while a gasket may also be seated in said recess for compression by said boss, and a coupling element yieldingly mounted 95 on one of said parts and adapted for fastening on the other, whereby a yieldingly fluid-tight joint may be maintained the nipple and thimble being operably separable to allow an escape of pressure.

9. In combination with a flexible train-pipe connection having hose sections provided with an intermediate coupling designed to be disconnected by the pulling apart of the hose sections when the cars are 110 separated, a normally fluid-tight or non-leakable pipe-joint in the train-pipe connection adapted to be opened by the pull of the hose to allow escape of fluid, thereby relieving the train-line pressure and allowing disconnection of the coupling without tearing the hose or damaging the train-pipe connection.

In testimony whereof I affix my signature, in presence of two witnesses.

WILDER R. SHECKLER.
